(57) **CLAIM**

The ornamental design for a curved center screen, as shown and described.

DESCRIPTION

FIG. 1 is a back view of a curved center screen, showing our new design.

FIG. 2 is a bottom view thereof.

FIG. 3 is a front view thereof.

FIG. 4 is an isometric view thereof.

FIG. 5 is a left-side view thereof.

FIG. 6 is a right-side view thereof.

FIG. 7 is a top view thereof; and,

FIG. 8 is a perspective view thereof in a state of use.

The broken lines showing a vehicle interior in FIG. 8 depict environmental structure which forms no part of the claimed design. The broken lines in FIGS. 1-8 show portions of the curved center screen which form no part of the claimed design.
